UNITED STATES PATENT OFFICE

CHARLES W. BRABBEÉ, OF BRONXVILLE, NEW YORK, ASSIGNOR TO AMERICAN RADIATOR COMPANY, OF NEW YORK, N. Y., A CORPORATION OF NEW JERSEY

BOILER

Application filed August 16, 1927. Serial No. 213,231.

My invention relates broadly and generally to new and useful improvements in boilers, and more particularly of the low pressure type such as are employed for heating water, 5 or for generating low pressure steam for circulation in a heating system including one or more heat-emitting elements commonly designated radiators.

Among other objects to be more fully set forth hereinafter, the invention contemplates the provision of a sectional boiler which will burn efficiently a variety of fuels, inclusive of both hard and soft coal, and in which the combustion of the fuel will be attended with 10 a minimum emission of smoke. A further object is to provide a boiler in which the heat of combustion will be efficiently and economically transmitted to the water-containing space or spaces, and consequently have a relatively high heat output in a heating system.

The invention consists in the improved construction and combination of parts and elements, to be more fully described hereinafter, and the novelty of which will be particularly 15 pointed out and distinctly claimed.

In the accompanying drawings to be taken as a part of this specification, I have illustrated a preferred embodiment of my invention, and in which drawings—

Figure 1 is a view in front elevation with part of the jacket or covering removed to show certain parts of the boiler proper;

Fig. 2 is a view in side elevation looking at the left-hand side of Fig. 1;

Fig. 3 is a view in side elevation looking at the right-hand side of Fig. 1;

Fig. 4 is a view in front end elevation of a portion of one of the center or intermediate sections of the boiler;

Fig. 5 is a view in side elevation of that portion of the section shown in Fig. 4;

Fig. 6 is a view in front elevation of a portion of two of the parts shown in Fig. 4 and showing a closure-plate applied thereto for closing the front end of a flue pass between two of the center or intermediate sections;

Fig. 7 is a vertical central section through the closure-plate shown in Fig. 6;

Fig. 8 is a view in side elevation of an end wall or section, the configuration of parts on

the inner surface thereof being indicated in dotted lines;

Fig. 9 is an enlarged detail view of the upper left-hand corner portion of Fig. 8;

Fig. 10 is a section on the line 10—10 of Fig. 9;

Fig. 11 is a view on a vertical intermediate section line through Fig. 1, showing one of the intermediate boiler sections in side elevation;

Fig. 12 is a view in side elevation showing the inner face of one of the end sections and showing in full lines the configuration of parts shown in dotted lines in Fig. 8;

Fig. 13 is a view in front elevation or edge view of the end section shown in Fig. 12;

Fig. 14 is a view in rear end or edge elevation of the section shown in Fig. 12;

Fig. 15 is a section view on the line 15—15 of Fig. 11 through one of the center or intermediate sections;

Fig. 16 is a section on the line 16—16 of Fig. 11;

Fig. 17 is a section on the line 17—17 of Fig. 11;

Fig. 18 is a section on the line 18—18 of Fig. 11;

Fig. 19 is an enlarged view in front elevation, partly in section, of a front wall or section containing the fuel feed port openings and clinker door openings;

Fig. 20 is a section on the line 20—20 of Fig. 19;

Fig. 21 is a section on the line 21—21 of Fig. 19;

Fig. 22 is a plan view of a grate element or bar employed in the door portion or primary combustion chamber of the boiler;

Fig. 23 is an end view of the grate bar shown in Fig. 22;

Fig. 24 is a side view of the grate bar shown in Fig. 22;

Fig. 25 is a view in side elevation of a center grate rest;

Fig. 26 is a plan view of the grate rest shown in Fig. 25;

Fig. 29 is a view in front elevation of a connecting member or coupling for connecting the grate rest shown in Fig. 25 to the front element shown in Fig. 19;

Fig. 30 is a central vertical section through the elements shown in Fig. 29;

Fig. 31 is an enlarged detail view in front elevation of a closure-member cooperating with an opening in the jacket to afford access to the ends of the intermediate boiler sections;

Fig. 32 is a section on the line 32—32 of Fig. 31;

Fig. 33 is an enlarged detail fragmentary view of the upper portion of one of the center sections showing a steam and water separating device employed when the boiler is operated generally to generate low pressure steam;

Fig. 34 is a section on the line 34—34 of Fig. 33, and

Fig. 35 is a section on the line 35—35 of Fig. 34.

Referring to the drawings by characters of reference, 1, 2 designate side sections or walls which in the preferred embodiment shown are arranged in parallel vertical planes, and which extend from front to rear of the boiler structure when considered in relative arrangement or position with respect to the fuel and ashpit doors to be presently described. Between the side sections 1 and 2 are a plurality of center or intermediate sections 3 arranged in planes parallel to each other and to the said side walls, and which extend from front to rear of the boiler. The said side and center sections combine to form the side, top and rear walls for a combustion chamber 4 and an ashpit chamber 5. The front portion of the boiler and of the combustion chamber 4 is closed by a front section or wall 6 which is water-backed or water-cooled and contains fuel feed or charge openings 7 and clinker clean-out openings 8. The internal chamber formed by the side, center and front sections just mentioned is divided by a suitable horizontal grate structure 9 so as to form the combustion space 4 and the lower ashpit chamber 5. The ashpit chamber is closed at the front by a suitable wall in the form of platework 10 having clean-out openings 11, through which ashes may be withdrawn from the ashpit.

Each of the center sections heretofore mentioned comprises a hollow member, preferably of cast-iron, which is adapted to hold in part the water to be heated or from which steam is to be generated, and includes a rear vertical column or water leg 12 which constitutes, in part, the rear wall of the boiler. Each vertical water leg is provided at a point adjacent its lower end or base with a hub member 13 having oppositely disposed annular flanges 14 formed with inwardly tapering surfaces 15 to receive tapered coupling nipp-

les 16 by which the section is coupled to the rear water leg of an adjacent section. At its upper portion the section includes a vertically extending hollow or chambered member 17, including vertical spaced walls 18, 18 to form an internal water space, said member being connected by upper, lower, and intermediate tubular members 19, 20, 21, respectively, with the said rear water leg, so that the water leg and the forwardly extending member 17 communicate through said tubular members. The said tubular members 20, 21 are spaced from each other to form a lower opening 22, said openings in the several sections when assembled forming a transverse distributing duct 23 which receives the hot gases from the combustion chamber in a manner to be presently described. The upper tubular member 19 is spaced from the intermediate tubular member to form an opening 24, which openings when the sections are assembled form a transverse outlet flue passage 25. The duct or flue 25 discharges into a smokehood 25^b adapted to be connected by suitable piping to a chimney. The openings 23, 25 are separated from each other by opposite ribs or flanges 26 extending from the water leg along the intermediate tubular member and lengthwise of the side face of the forwardly extending water member 17, so that the hot gases entering the distributing chamber will flow lengthwise of the forwardly extending member and then be reversed to flow rearward and into the transverse outlet flue passage. Each vertical water leg member is provided with a joint rib or flange 27 extending lengthwise thereof and continued along the horizontal upper edge portion of the section, so that the side faces of the water-containing members 17 are spaced from each other to form upper and lower gas flow passages 28, 29 connecting the distributing duct with the outlet flue duct 25. The forwardly extending portions constituted by the water members 17, constitute the crown wall of the combustion space or chamber of the boiler, and the lower edge portions of the forwardly projecting members are provided with lateral flanges or ribs 30, 30, which when the sections are assembled contact the corresponding ribs on adjacent sections to complete the crown wall of the combustion space and prevent the gaseous products of combustion from passing directly from the chamber 4 into the lower gas passage 29. The lower tubular members 20 are of less external diameter than the maximum thickness of the section (see Fig. 18), so that when the sections are assembled these tubular members will be spaced from each other to form flow passages, thus permitting gaseous products from the combustion chamber to flow between these tubular members into the distributing duct 23 and thence forwardly into the lower gas passage 29. The forward

ends of the members 17 extend to a point adjacent the front of the boiler, and the open ends of the gas passages are closed in a manner to be presently described, so that the forwardly flowing gases will be reversed and caused to flow rearwardly through the gas passages 28 to the transverse flue passage 25. It will be noted that in the embodiment shown these intermediate sections extend longitudinally from front to rear of the boiler and the side ribs on said sections contact laterally to form the gas passages between the sections.

Each of the center sections just described is provided with a depending tubular member which is internally in communication with the interior of the body of the section and depends from the forwardly extending portion of the section, preferably in advance of the lower tubular members 20. These depending tubular members are so located and constructed that when the intermediate sections are assembled, said depending members align transversely of the boiler to form a transverse baffle dividing the chamber above the grate to form the forward main combustion chamber 4 and a rear secondary combustion chamber and outlet passage 31. In the preferred embodiment the depending baffle-forming member on each section comprises a forward hollow member 32 which inclines downwardly and rearwardly to a point above the fire bed on the grate, and a rearward forwardly depending member 33 which is united at its lower end to the lower end portion of the forwardly extending member 32. At the point where the forward baffle member 32 and the rearward baffle member 33 unite, they communicate with a hollow coupling member 34 having side nipple openings 35 to receive oppositely tapered coupling nipples 36, by means of which the baffle members on adjacent sections are connected and sealed to each other. The baffle members 32, 33 and the coupling member 34 are hollow and communicate with each other, and the upper ends of said baffle members communicate respectively with the interior of the lower portion of the forward member 17 and member 20, so that the water in the boiler is caused to circulate through the baffle members and the chamber around the nipple couplings. The baffle members 32, 33 in each section are spaced from each other to form an opening 37, so that when the intermediate sections are assembled and the baffle structures are arranged in alignment, the openings 37 in adjacent sections will register to form a transverse air supply duct extending through the baffle and transversely of the plane of the intermediate sections of the boiler.

The forward baffle member 32 on each section, is provided with opposite side flanges or beads 38 forming continuations of the flanges 30, said flanges 38 being directed or

curved downwardly and rearwardly to a point beneath the nipple couplings heretofore described. Extending rearwardly from the flanges 30 on each section and bounding the upper and rear portion of the opening 37, is a rib or flange 39 which extends longitudinally of the rear baffle member, and at its lower end merges in an annular rib 40 surrounding the said nipple opening. The annular rib surrounding the nipple opening is joined to a short depending rib 41 which terminates at a point spaced from the lower end portion of the rib 38, the arrangement being such that the baffle is provided on opposite sides of each section and between the sections with outlet ducts 42 communicating with the transverse opening or duct 37, and adapted to discharge air from said duct 37 at a point adjacent the bottom of the baffle. By directing the rib 38 downwardly and rearwardly, as shown in Fig. 11, the said ducts 42 serve to direct the air in streams or jets toward the secondary combustion or outlet chamber 31. It will also be seen that when the sections are assembled the ribs 38, 39, 40 and 41 on one section contact the corresponding ribs or flanges on an adjacent section to enclose the air duct 37, thus preventing the passage of air therefrom, except through the outlet ducts 42.

Each of the end sections or walls comprises inner and outer spaced walls 43, 44, united by a marginal wall 45 to form an internal water chamber which forms part of the water-containing space of the boiler. The outer wall of each side section is substantially flat, but the inner wall is preferably constructed, as shown in Fig. 12, with a rear vertical column or leg portion 46 corresponding to the vertical water legs 12 on the intermediate sections, and having a longitudinal rib 47 which cooperates with the corresponding bead on the next adjacent intermediate section to close the rear portion of the boiler. The inner wall is also provided at its upper edge portion with a horizontal rib 48 to contact the corresponding rib 27 on the center section to maintain the side sections spaced from the center section to form the gas passage 28 between the side section and the center section. The side section is also formed with forwardly extending tubular members 19^a, 20^a, 21^a corresponding to the members 19, 20, 21 on the center section, and with a rib member 26^a corresponding to the rib 26 on the center section, as well as the lower horizontal rib 30^a to cooperate with the rib 30 on the adjacent center section to complete the crown wall of the main combustion chamber. The side section is also provided with hollow ribbed baffle-forming members 32^a, 33^a and a coupling nipple 36^a similar to the baffle-forming members 32, 33 on the intermediate section and adapted to cooperate with the latter to complete the transversely

extending baffle wall. The side section is provided at a point above the baffle or rib 26^a with an opening 25^a which delivers the combustion products from the gas passages 28^a, 29^a to the outlet flue or pipe, but there is no opening between the lower tubular member 20^a and the intermediate tubular member 21^a, as is the case with the intermediate sections. The side wall is provided at a point in alignment with the opening forming the air duct in the transverse baffle, with an air supply opening 49 which admits a supply of secondary air from a point external of the boiler to the transverse duct 37 when the end sections and intermediate sections are assembled. The end sections may each be formed with a sight opening 50 located in line with the secondary or outlet chamber 31. The end section is provided with a lower, water-backed portion 51 which serves to close the sides of the ashpit chamber, and the inner wall of the section beneath the grate is provided with a coupling hub 52 having an inwardly tapering opening 53 adapted to receive a tapered push nipple 54, by means of which the end section may be coupled to the hub 13 at the lower end of the vertical water leg of the next intermediate section.

The forwardly extending member 17 of each intermediate section is provided at its upper portion with a coupling hub 55, and the end sections are similarly provided, said hubs being so arranged as to align transversely of the boiler when the sections are assembled. These coupling hubs are provided with surrounding contact ribs 56 with inwardly tapering openings 57 to receive oppositely tapered nipples 58, by means of which the sections are united at this point. These coupling nipples 58 align to form the outlet passages 58^a for either the hot water or the steam supplied by the boiler, and the outer wall of each side section is provided with an opening 59 which aligns with the openings through the hubs 55 and may be tapped to receive a screw plug 60 (Fig. 8), or to receive a temperature or pressure-operated damper regulator 61, as shown in Fig. 3. Each of the nipples 58 heretofore described, is provided at its lower portion with an internal lug 62, and seated in the ends of the nipples in each section (see Figs. 33 and 34), is a steam separating member in the form of a sleeve 63, the ends of which are inserted in the ends of the nipples, and which sleeve is provided on its upper side with a longitudinal slot or cutaway portion 64 to permit access of the generated steam to the interior of the sleeve. One end of each sleeve is provided with a recess or notch 65 which receives the lug 62, whereby the sleeve is held against rotation and the slot 64 maintained in its upper position. The lugs 62 also prevent endwise movement of said sleeves. It will be understood that when the

boiler is assembled, there is a sleeve 63 located in each section and extending across the steam space therein, so that said sleeves and the connecting nipples 58 form a steamway extending across all of the intermediate sections of the boiler, and opening at its end into the end sections. It will be noted by reference to Figs. 8, 11 and 12, that the separating sleeves are arranged above the water line of the boiler, and being imperforate or solid on their side and lower portions, prevent water from entering the outlet passage or steamway. Steam, however, is permitted to pass over the sleeve and into the steamway through the slots 64. These sleeves are preferably employed only when the boiler is used for generating steam, but if the boiler be only used for heating hot water for a hot water heating system, these sleeves may be omitted.

Within the upper portion of each side and center section above the water line, is a cross baffle or diaphragm 17^a uniting, and preferably cast integral with the side walls and extending forwardly from a point beneath the hubs 55 to a point adjacent the forward ends of the baffles or ribs 26, 26^a. This cross-baffle serves to prevent water globules rising to a point where they might enter the openings 64 in the sleeves 63, and also causing the steam to flow forward and then rearward in the section and during such flow deposit entrained water before reaching the said openings 64. This baffle also causes the steam and entrained water to strike the wall of the hollow sleeve whereby the entrained water is deflected and returned to the body of water in the section. By this means comparatively dry steam enters said sleeves and is delivered to the heating system, and the delivery of wet steam is reduced or prevented so that throwing of water into the heating system is obviated. A small baffle 17^b is also cast in the section in rear of each of the sleeves, so as to prevent the steam in the rear portion of the section from flowing directly into the sleeve opening 64 but causing the same to be deflected downward against and beneath the wall of the sleeve and then be directed forwardly.

At the forward ends of the intermediate sections the front ends of the gas passages 28, 29, 28^a, 29^a are closed by detachable closure plates 65 which are provided on their vertical side edges with laterally projecting pins 66 which are adapted to be inserted in bayonet slots 67 cast in the side faces of the intermediate sections. The plates are applied in position by placing the plates against the ends of the sections, with the pins 66 entered in the horizontal portions of the bayonet slots, and said plates may then gravitate or be moved downward so that they are held in place by interengagement of the pins with the vertical front wall of the slots. These

plates close the spaces between the sections and cause the forwardly flowing gases to travel upward and rearward through the spaces between the sections into the flue outlet passage 25. It will be understood that each end section is also provided with a similar bayonet slot so that a closure-plate may be applied to cover the opening between each end section and the next adjacent intermediate section.

The front portion of the boiler is closed by a hollow or water-backed section 6 (see Figs. 11 and 19 to 21), consisting of a substantially rectangular member, including front and rear spaced walls 68, 69 united by a marginal wall 70 to form the water-enclosing space. Through these walls are formed the charging door openings 7 to be closed by suitable doors 71 hinged suitably to the front wall of the section. The front section may be also provided with the clinker clean-out openings 8 controlled by suitable doors 72 hinged suitably on the section. The section is held in place by means of upper and lower nipple connections 73, preferably of the double tapered push-nipple type, the nipples being seated in correspondingly tapered hubs 74 formed in the adjacent vertical portions of the end sections and the marginal walls of the front section. By these nipple connections the space within the front section is connected in the water circulation or containing space of the boiler so that water is circulated through the front section and serves to keep the same cool. The front section is also supported at its lower portion by bracket lugs 75 secured by bolts 76 passing through sleeves 77 cast in the end sections and clamped in place by nuts 78 (see Fig. 19).

At its front central portion the front section is provided with a vertical elliptical recess 79 closed at its rear upper portion by a wall 80 having bolt holes 81. This recess is adapted to receive a water-cooled grate support member 82 consisting of a cored casting, which when in place in the recess is held in place by bolts 83 passing through openings 84 in the support member, and the holes 81. The inner wall of the grate rest member is provided at its upper portion with a water circulation opening 85 which registers with an opening 86 in the wall 80, and is secured thereto by a tapered nipple 85^a. The lower portion of the inner wall of the rest is provided with a circulation opening 87 in register with a through opening 88 in the front section located beneath said wall 80. Extending longitudinally of the boiler is a water-cooled hollow center grate rest 89, provided at one end with a flange 90, by which it is bolted at its rear end, as at 91, to one of the intermediate sections, and at its forward end this grate rest is formed with a tapered port 92 to receive a coupling nipple 92^a, which is also seated in

the tapered opening 87 in the support 82. The arrangement is such that water may circulate through the horizontal grate rest 89 to and from the center section and the hollow front section. The center grate rest 89 is provided on opposite sides with lugs or pivots 93, and the inner faces of the side sections or walls are provided with corresponding lugs 94, upon which are mounted rocking grate bars 95, the ends of the bars being provided with recesses 96 to receive said lugs. The grate bars are also provided with depending arms 97 having pivots 98 arranged in recesses 99 in reciprocable grate operating bars 100, by means of which the grate bars may be rocked or tilted when desired. As will be noted from Fig. 11 of the drawings, wherein seven grate bars are shown, the forward five bars, or those bars in advance of the secondary combustion chamber 31, are perforated to permit ashes to descend therethrough, and primary air for combustion to ascend from the ashpit into the primary combustion chamber, but the rear two bars, or those beneath the secondary combustion chamber 31 are imperforate. Preferably, the imperforate bars are operated by one operating bar 100, and the perforate bars by separate or independent operating bars 100^a, so that the perforate and imperforate bars may be operated independently of each other. The grate operating bars are extended to the front of the boiler where they may be operated by any well known form of operating lever 101 fulcrumed, as at 102, on the platework 10. The platework 10 serves to close the front of the ashpit chamber, and is provided with openings 11 through which access may be had to the ashpit for the purpose of removing ashes. The ashpit openings are closed by doors 103 hinged on the platework.

The outlet from the boiler may be, if desired, through a coupling 104 arranged on the top of the boiler and communicating through one of the sections with the cross-passage 58 through nipples 58 and sleeves 63 heretofore described, whereby the water or steam may be piped to the heating system, or the end sections may be provided with outlet tappings 105 to receive piping (not shown) leading to the heating system. The return from the heating system may be through a coupling 106 communicating with and bolted to one of the water legs of an intermediate section, or may be through tappings 107 at the base of the end sections. It will be understood that the inlet or outlet flow tappings which are not utilized, may be plugged by suitable screw plugs (not shown). It will be understood that the outlets and inlets or returns may be used either singly or in such combinations as the installation may require.

One of the side sections on a point be-

neath the grate, is provided with an inlet draft opening 108 to supply air for combustion into the ashpit. This opening is surrounded by a door frame 109 and is controlled by a gravity closed rocking damper-plate or door 110 pivoted on said frame. The outlet hood or pipe section 25^a is provided on one side with a check damper opening 111 controlled by a rocking check damper 112. The damper regulator 61 heretofore described is of well known form, and acts on a lever 113 which is connected by flexible chain connections 114, 115 to the draft control damper 110 and the check control damper 112, so as to automatically reduce the draft and open the check damper when it is desired to lower the rate of combustion, or to close the check and open the draft damper when it is desired to increase the rate of combustion. It will be understood that in the case of a steam generating boiler, an increase of steam pressure above a determined or desired amount, will cause the regulator to cut down the rate of combustion, and a fall of steam pressure below the point desired will operate the dampers to increase the rate of combustion.

The boiler may be enclosed in a suitable jacket 116 having cut-out portions or openings to correspond with the flow openings and passages to and from the sections, the construction of this jacket in general being immaterial. However, the front jacket wall is preferably provided at its upper portion with a transverse opening 117 permitting access to the detachable plates 65, so that a suitable cleaning implement may be inserted in the gas passages 28, 29 for cleaning purposes. This opening 117 is adapted to be closed by a cover member 118 (see Figs. 31 and 32) adapted to be secured in place by bolts 119 passing through openings therein and threaded into sockets 120 in the forward vertical portions of the intermediate sections (see Figs. 4 and 5).

The end of duct 25 opposite to that opening into the hood is closed by a clean-out door 25^c hinged to a frame 25^d bolted, or otherwise secured to the outer wall of the end section. The opening 108 in the end section opposite to that having the damper 110 may be closed by a cover-plate 108^a suitably secured to the jacket. The side members of the jacket are also provided with pivoted closure members 37^a or plate dampers overlying the ends of the duct 37 and operable to control the ingress of air to the said duct. The side members of the jacket are also provided with pivoted closures 50^a containing sight glass 50^b and adapted to close or open the peep openings 50 in the side sections. The end and intermediate sections are held in assembled relation by tie-rods 121 passed through openings 122 in lugs or bosses 123 cast integral with said sections and held in

place with nuts 124 (see Fig. 9) on the ends of said rods in any suitable manner well known in sectional boiler practice.

The operation of this boiler is as follows: A bed of suitable fuel, such as coal, is charged through the door openings 7 into the combustion space in front of the baffle structure 32, 33 and is kindled in any suitable manner. When the coal has burned long enough to become coked, the operator pushes the hot incandescent coke rearward so as to close the space between the lower portion of the baffle structure and the grate, so that the products of combustion will be compelled to flow through this bed of hot coke before passing into the secondary combustion chamber or outlet passage 31, causing combustible matter carried by the gases to be, to a considerable extent, consumed by contact with the hot coke. During the firing or charging period, when the emission of so-called smoke is at its maximum, the air-control doors 37^a may be opened to furnish secondary air to the air supply duct 37, the air being drawn in by the draft and through the outlet ducts or jets 42 into the hot coke and into the gases passing beneath the baffle, this air serving to cause more complete combustion of unburned matter carried by the gases, and reduce to a minimum the amount of so-called smoke emitted from the boiler. The hot gases from the secondary combustion chamber 31 flow upward into contact with the tubular members 20, 20^a and are deflected through the spaces between the same, passing into the transverse distributing chamber or duct 23. From the distributing chamber 23 the hot gases pass forward through the lower gas passages 29, 29^a, imparting their heat to the walls of the sections and heating the water therein. The gases flow forward to the front ends of the sections and then pass upward around the forward end of the baffles 26 and then rearward to the discharge duct 25, through which they pass to the outlet hood or pipe 25^b. It will be understood that the supply of air through the baffle is available at any time when desired or necessary, by opening or closing the closure-plates 37^a, and that the amount of secondary air may be regulated by adjusting the plates to vary the area of the inlet ports to the cross duct 37 in the baffle. It will be seen that the gases which rise from the fuel into the dome of the forward or main combustion chamber, are deflected by the baffle downward through the incandescent coal and coke at the base of the baffle, whereby combustible constituents of the gases are subjected to further combustion, and, further, such gases are subjected to an additional supply of air from the baffle, substantially completing the combustion in the space to the rear of the baffle.

The rear grate sections 95^a are made imperforate so as to reduce the primary air

supply in rear of the baffle in order to conserve the incandescent coke on said sections 95^a as long as possible. If these grate bars were open like the forward bars, the coke 5 would burn out prematurely and the ash dropping through the bars would uncover the same, thereby permitting cold primary air to rush up into the chamber or passage 31. It will be understood, however, that the im- 10 perforate grate sections may be tilted to dump the coke or ash into the ashpit cham- ber when desired.

One of the side sections may be provided with tappings 125 for connection to a water 15 level gauge glass 126, and with tapping 127 for tri-cocks 128.

The construction and arrangement is ad- 20 vantageous in that by forming the intermediate sections each with its own element 25 of the baffle, the location of the baffle will be at the most advantageous point, irrespective of the number of sections which may be as- 30 sembed to provide a boiler of a given capac- ity or rating. Furthermore, by arranging 35 the sections so as to extend lengthwise of the boiler, and providing each of the sections with a baffle forming a part which alines 40 transversely of the direction of flow of the gases, the flues can be calculated so that cor- 45 rect areas will be provided, irrespective of the number of sections and the area of the 50 grate surface, this being accomplished by cal- 55 culating the flue area of each section in proper proportion to the grate area of each 60 section.

While I have shown and described my in- 65 vention as being applicable for generation of steam, it will be understood that the same is not to be limited to such use, but may be 70 employed with facility and advantage for heating water for circulation in a water heat- 75 ing system without in any way departing from the intended scope of the appended 80 claims. In several of the figures of the draw- 85 ings I have indicated by suitable legend the water line when the boiler is employed for 90 generation of steam, but it will be understood that when the boiler is operated for heating 95 of water for a water heating system, the sec- 100 tions will be completely filled with water.

What I claim and desire to secure by Let- 105 ters Patent of the United States is:—

1. A boiler comprising a grate, a plu- 110 rality of sections arranged side by side, cer- 115 tain of said sections each having a depend- 120 ing water member communicating therewith and terminating at its lower end above the 125 grate, each of said members having a trans- 130 verse opening, said depending water mem- bers being arranged side by side and cooper- 135 ating to form a depending baffle extending transversely of the normal plane of said sec- 140 tions and dividing the space above the grate into two chambers arranged one to the rear 145 of the other, said transverse openings alin-

ing communicatively to form a duct extending through said baffle, and means at the lower portion of said baffle for discharging a combustion supporting gas from said duct.

2. A boiler comprising a grate, a plurality 70 of sections arranged side by side, certain of said sections each having a depending water member communicating therewith and terminating at its lower end above the grate, each of said members having a transverse opening, said depending water members being arranged side by side transversely of the boiler and cooperating to form a baffle extending transversely of the normal plane of said sections and dividing the space above the grate into chambers one to the rear of the other, said transverse openings alining communicatively to form a duct extending through said baffle, and a plurality of ducts 75 extending downward through said baffle and serving to discharge from said duct a combustion-promoting gas at the lower portion of said baffle.

3. A boiler comprising a grate, a plurality 80 of sections arranged side by side transversely of the boiler, certain of said sections each having a depending water member communicating therewith and terminating at its lower end above the grate, said depending water members being arranged side by side and co- 85 operating to form a baffle extending trans- 90 versely of the normal plane of said sections and dividing the space above the grate into chambers one to the rear of the other, and a plurality of ducts extending downward 95 through said baffle and having discharge end portions curved toward the rear of the baffle and arranged to discharge a combustion-promoting gas toward said rearward chamber.

4. A boiler comprising a grate, a plurality 100 of sections arranged side by side, certain of said sections each having a depending water member communicating therewith and terminating at its lower end above the grate, each of said members having a transverse 105 opening said depending water members being arranged side by side and cooperating to form a baffle extending transversely of the normal plane of said sections and dividing the space above the grate into chambers one 110 to the rear of the other, the said transverse openings alining communicatively to form a duct extending through said baffle, and flanges on said depending water members and 115 cooperating to form downwardly extending passages communicating with said duct for discharging a combustion-promoting gas from said duct at the lower portion of said baffle.

5. A boiler comprising a grate, a plurality 120 of sections arranged side by side, certain of said sections each having a depending water member communicating therewith and terminating at its lower end above the grate, said depending water members being ar- 125 130

ranged side by side and cooperating to form a baffle extending transversely of the normal plane of said sections and dividing the space above the grate into forward and rearward chambers, said sections including members in front of said baffle constituting the crown wall of said forward chamber.

6. A boiler comprising a grate, a plurality of sections arranged side by side, certain of said sections each having a depending water member communicating therewith and terminating at its lower end above the grate, said depending water members being arranged side by side and cooperating to form a baffle extending transversely of the normal plane of said sections and dividing the space above the grate into chambers one to the rear of the other, said sections including members arranged in contact with each other in front of said baffle to form a closed crown wall for said forward chamber, and said sections including members spaced apart in rear of said baffle to provide for flow of combustion products from said rearward chamber.

25 7. A boiler comprising a grate, a plurality of sections arranged side by side, certain of said sections each having a depending water member communicating therewith and terminating at its lower end above the grate, said depending water members being arranged side by side and cooperating to form a baffle extending transversely of the normal plane of said sections and dividing the space above the grate into chambers one to the rear of the other, a plurality of ducts extending downward through said baffle and serving to discharge a combustion promoting gas at the lower portion of the baffle, and a closed duct formed by said depending water members and supplying the said gas to the first-named ducts.

40 8. A boiler comprising a grate, a plurality of sections arranged side by side, certain of said sections each having a depending water member communicating therewith and terminating at its lower end above the grate, said water members being arranged side by side and cooperating to form a baffle extending transversely of the normal plane of said sections and dividing the space above the grate into chambers one to the rear of the other, a plurality of ducts extending downward through said baffle and serving to discharge a combustion promoting gas at the lower portion of the baffle, and a closed duct formed by coacting flanges on said depending water members and supplying the said gas to the first-named ducts, said closed duct having an inlet opening through a wall of the boiler.

55 9. A boiler comprising a grate, a plurality of sections arranged side by side, certain of said sections each having a depending water member communicating therewith and terminating at its lower end above the grate, said depending water members being arranged

side by side to form a baffle extending transversely of the normal plane of said sections and dividing the space above the grate into chambers one to the rear of the other, and water flow connections communicatively connecting the lower end portions of said depending water members to each other.

70 10. A boiler comprising a grate, a plurality of sections arranged side by side, certain of said sections each having a depending water member communicating therewith and terminating at its lower end above the grate, said depending water members being arranged side by side and cooperating to form a baffle extending transversely of the normal plane of said sections and dividing the space above the grate into chambers one to the rear of the other, and alining flow nipples communicatively connecting the lower end portions of said members to each other.

75 11. A boiler comprising a grate, a plurality of sections arranged side by side, certain of said sections each having a depending water member communicating therewith and terminating at its lower end above the grate, said water members being arranged side by side to form a baffle extending transversely of the normal plane of said sections and dividing the space above the grate into chambers one to the rear of the other, flow connections communicatively connecting the lower end portions of said depending water members to each other, and a plurality of closed ducts extending downward between said depending water members and serving to discharge a combustion promoting gas at the lower portion of said baffle.

80 12. A boiler comprising a grate, a plurality of sections arranged side by side, certain of said sections each having a depending water member communicating therewith and terminating at its lower end above the grate, said depending water members being arranged side by side and cooperating to form a baffle extending transversely of the normal plane of said sections and dividing the space above the grate into chambers one to the rear of the other, and each of said depending water members having oppositely disposed openings at its lower portion, said openings being in alinement transversely of the baffle, and said members being sealed to each other about said openings to form a water flow passage between said members.

85 13. A boiler comprising a grate, a plurality of sections arranged side by side, certain of said sections each having a depending water member communicating therewith and terminating at its lower end above the grate, said depending water members being arranged side by side and cooperating to form a baffle extending transversely of the normal plane of said sections and dividing the space above the grate into chambers one to the rear of the other, each of said depending water members

having oppositely disposed openings at its lower portion, said openings being in alignment transversely of the baffle, and said members being sealed to each other about said openings to form a flow passage between said members, and flanges on opposite sides of each depending water member and cooperating with an adjacent water member to form a closed duct extending downward through the baffle and serving to discharge a combustion promoting gas at the lower portion of the baffle.

14. A boiler comprising a grate, a plurality of sections arranged side by side, certain of said sections each having a depending water member communicating therewith and terminating at its lower end above the grate, said water members being arranged side by side to form a continuous baffle extending transversely of the normal plane of said sections and dividing the space above the grate into chambers one to the rear of the other, said sections having members arranged in contact with each other in front of said baffle to form a closed crown wall for said forward chamber, and said sections having members spaced apart in rear of said baffle to provide passages for flow of combustion products from said rearward chamber, and said sections being formed to provide flow passages for passing products of combustion in contact with said sections above the said crown wall, said passages receiving the combustion products from said rearward chamber.

15. A boiler comprising a grate, a plurality of sections having means coacting to form a crown wall structure including water spaces and intervening gas flow spaces, and a baffle depending from the crown wall structure and dividing the space above the grate into chambers one to the rear of the other, said baffle including a plurality of depending water members arranged side by side and contacting each other along their longitudinal edges to form a closed wall extending transversely of the normal plane of said sections, and directing products of combustion from the forward chamber beneath said baffle into the rearward chamber.

16. A boiler of the character described comprising a surrounding wall structure and a substantially horizontal grate, a plurality of sections arranged side by side and including horizontal water passage members located above the grate to form the crown wall of a main fuel chamber, each of said sections having a depending water tube member communicating therewith and extending toward the grate, said depending water tube members coacting to form a baffle extending transversely of the normal plane of said sections and located at the rear of the main fuel chamber, and means carried by said depending water tube members forming

air passages delivering air at the lower portion of said baffle.

17. A boiler of the character described comprising a surrounding wall structure and a substantially horizontal grate and a plurality of sections arranged side by side and including horizontal water passage members located over the grate to form the crown wall of a main fuel chamber, a water tube member depending from and extending across the full width of each of said members and communicating therewith and extending toward the grate, said depending water tube members coacting with each other at their opposite longitudinal side edges to form with said crown wall a continuous baffle having its upper edge portion meeting said crown wall to close the space between said baffle and wall and prevent flow therebetween, said baffle extending transversely of the normal plane of said sections and located at the rear of the main fuel chamber.

18. A boiler comprising a grate, a plurality of sections arranged side by side, certain of said sections each having depending water members terminating at their lower ends above the grate, said depending water members being arranged side by side and cooperating to form a water-backed baffle extending transversely of the normal plane of said sections and dividing the space above the grate into chambers one to the rear of the other, and said members cooperating to form in said baffle a closed air duct extending transversely of said grate, and outlet means extending downward through said baffle and adapted to receive air from said first-named duct and discharge the air at the lower portion of the baffle.

19. A boiler comprising a grate, side walls, a plurality of intermediate sections, each of which includes an upright member and a forwardly extending member, the upright members cooperating to form a rear wall of the boiler, and the forwardly extending members forming the crown wall of the boiler, certain of said intermediate sections being provided with depending water members terminating above the grate, said depending water members cooperating to form a baffle extending transversely of the normal plane of said sections and dividing the space above the grate into a combustion chamber and an outlet chamber, and portions of said forwardly extending members being spaced from each other to form gas passages communicating with said outlet chamber.

20. A boiler comprising a grate, side walls, a plurality of intermediate sections, each of which includes an upright member and a forwardly extending member, the upright members cooperating to form a rear wall of the boiler, and the forwardly extending members forming the crown wall of the boiler, certain of said intermediate sections

being provided with depending water members terminating above the grate, said depending water members cooperating to form a baffle extending transversely of the normal plane of said sections and dividing the space above the grate into a combustion chamber and an outlet chamber, portions of said forwardly extending members being spaced from each other to form gas passages communicating with said outlet chamber, and means for causing the gases to flow circuitously through said gas passages.

21. A boiler comprising a grate, side walls, a plurality of intermediate tubular sections, each of which includes an upright member and a forwardly extending member, the upright members cooperating to form a rear wall of the boiler, and the forwardly extending members forming the crown wall of the boiler, certain of said intermediate sections being provided with depending water members terminating above the grate, said depending water tube members cooperating to form a water-backed baffle extending transversely of the normal plane of said sections and dividing the space above the grate into a combustion chamber and an outlet chamber, and said forwardly extending members being spaced from each other to form gas passages communicating with said outlet chamber, portions of said forwardly extending portions having cooperating flange members dividing said gas passages to cause the gases to flow circuitously over said forwardly extending members.

22. A boiler comprising a grate, side walls, intermediate sections and a front wall, each of said intermediate sections including an upright member and a forwardly extending member, said upright members cooperating to form a rear wall of the boiler and the forwardly extending members cooperating to form the crown wall of the boiler and certain portions of said forwardly extending members being spaced from each other to form gas flow passages, certain of said intermediate sections having depending water members terminating at their lower ends above the grate, said depending water members operating to form a baffle extending transversely of the normal plane of said sections and dividing the space above the grate into a combustion chamber and a rearward outlet chamber, said depending members enclosing an air duct extending transversely of the boiler and having outlet means for delivering air from said duct, spaced water members connecting said upright members with said forwardly extending members and affording communication between said outlet chamber and said gas flow passages, registering openings in said sections above said spaced water members to form a flue outlet duct from the gas flow passages to cause gases from the rearward outlet chamber to flow forwardly

in said gas flow passages and then rearwardly to said flue outlet duct.

23. In a boiler, a plurality of water-containing sections constituting a water space and a steam space for the boiler, a tubular steam outlet member in the steam space and having a steam-receiving opening in its upper portion, and an inclined baffle member in certain of said sections above the water line therein and extending forwardly from said outlet member for preventing direct entrance of steam into said opening and causing the generated steam to strike against said outlet member whereby entrained water is deflected and returned to the body of water, and the steam is separated and enters said steam-receiving opening.

24. In a boiler, a plurality of water-containing sections having registering openings in opposite walls thereof, and a removable open-ended tubular member extending at its opposite ends into said openings and bridging the space above the water line in certain of the sections and connecting said openings, said tubular member being supported at its opposite ends in said openings and having a steam-receiving opening within its section in the upper portion thereof.

25. In a boiler, a plurality of water-containing sections having registering openings in opposite walls thereof, an open-ended tubular member bridging the space above the water line in certain of the sections and connecting said openings, said tubular member having a steam receiving opening in the upper portion thereof, and baffling means in said space to intercept the flow of steam to said tubular member.

26. In a boiler, a plurality of water-containing sections having registering openings in the adjacent walls thereof, tubular members extending into and supported at their opposite ends in said openings and bridging the space above the water line in said sections and connecting said openings to form a continuous steam outlet passage extending transversely of said sections, said members having steam-receiving openings within said sections in the upper portions thereof.

27. In a boiler, a plurality of water-containing sections spaced from each other to provide passages to receive gases from the combustion chamber, said sections having openings in the side walls thereof, nipples in said openings to connect the space above the water line in said sections, and an open-ended tubular member bridging the space in certain of the sections and supported by said nipples, said tubular member having a steam-receiving opening in the upper portion thereof.

28. In a boiler, a plurality of water-containing sections spaced from each other to provide passages to receive gases from the combustion chamber, said sections having registering openings in the side walls thereof,

nipples in said openings to connect the space above the water line in said sections, and an open-ended tubular member bridging the space in certain of the sections and sleeved in said nipples, said tubular member having a steam-receiving opening in the upper portion thereof, certain of said nipples having an internal projection, and said tubular member having a recess receiving said projection.

10 29. A boiler of the character described comprising intermediate sections and walls enclosing a combustion space, said intermediate sections each including a vertical rear water leg and a forwardly extending hollow

15 member, said hollow members being laterally spaced to provide gas flow passages, upper, lower and intermediate tubular members connecting the water leg of each intermediate section to said hollow member, and forming 20 upper and lower gas flow cross ducts, and said lower tubular members being spaced to afford communication between said combustion space and said gas flow passages.

30. A boiler of the character described 25 comprising intermediate sections and walls enclosing a combustion space, said intermediate sections each including a vertical rear water leg and a forwardly extending hollow member, said hollow members being laterally

30 spaced to provide gas flow passages, upper, lower and intermediate tubular members connecting the water leg of each intermediate section to said hollow member, and forming an upper outlet cross-duct and a lower distributing cross-duct, means to separate said cross-ducts, and said lower tubular members being spaced to afford communication between said combustion space and said distributing cross-duct.

40 31. A boiler of the character described comprising intermediate sections and walls enclosing a combustion space, said intermediate sections each including a vertical rear waterleg and a forwardly extending hollow

45 member, said hollow members being laterally spaced to provide gas flow passages, upper, lower and intermediate tubular members connecting the water leg of each intermediate section to said hollow member and

50 forming upper and lower gas flow cross-ducts, means to separate said cross-ducts, said lower tubular members being spaced to afford communication between said combustion space and said gas flow passages, and each of said intermediate sections being pro-

55 vided with a depending water tube, said depending water tubes alining with each other to form a baffle extending transversely of the normal plane of said sections and dividing 60 the combustion space into a main combustion chamber, and an outlet chamber delivering hot gases through the spaces between said lower tubular members to said lower cross flow duct.

65 32. A boiler of the characted described

comprising end sections, intermediate sections and a front section enclosing a combustion space, said intermediate sections each including a vertical rear water leg and a forwardly extending hollow horizontal member, 70 said horizontal members being spaced to form gas flow passages, ducts connecting said gas flow passages with said combustion space, said gas flow passages being open at the forward end of the boiler, and upright closure 75 plates closing the forward ends of said gas flow passages, said closure plates having a pin and bayonet slot connection with said sections.

In testimony whereof I have hereunto sub- 80 scribed my name.

CHARLES W. BRABBÉE.
